MIXING DEVICE

Erwin G. Baker, Indianapolis, Ind.

Application September 30, 1938, Serial No. 232,514

5 Claims. (Cl. 48—180)

This invention relates to means for breaking up any unvaporized globules of fuel and minutely atomizing all molecules of hydrocarbon vapors and air for explosion in internal combustion engines, after the mixture of fuel and air has left the carburetor and before it has reached the explosion chamber of the engine. It is adapted for motor car, airplane, stationary and all hydrocarbon explosive engines.

10 Manifestly the finer the atomization of the hydrocarbon vapors the more intimately they may be made to contact and mix with the air supplied to it at the carburetor and the quicker and more perfect the combustion will be when 15 the mixture is fired.

The object of this invention is to provide a device with numerous sharp edges against which the rushing mixture will be impacted and its 20 molecules cut and broken into small particles, and in which vacuum recesses will be provided between the cutting edges into which the vapors will be drawn and with walls against which the separated atoms will be swirled to intimately mix the hydrocarbon vapors with the air.

25 A further object is to hold the device in the most effective position under the discharge side of the butterfly valve and to produce a Venturi action with the device which will accelerate the movement of the vapors through the intake manifold into the engine.

Another object is to provide a device which can be made and sold independently of the engine on which it is to be used, and to provide an efficient fuel mixer at a low cost.

35 I accomplish the above and other objects which will hereinafter appear, by the means illustrated in the accompanying drawing, in which

Fig. 1 is a fragment in elevation and vertical section of an intake manifold of an engine with 40 my device applied; and

Fig. 2 is a top plan view of same on the line 2—2 of Fig. 1 showing my device broken away in part and showing my preferred manner of supporting it in the intake manifold.

45 Like characters of reference indicate like parts in the two views of the drawing.

My vacuum vaporizer comprises preferably a solid, and substantially double cones 3 and 4 with their bases contacting and integral. The 50 surfaces of both cones are formed with a close series of deep annular channels 5, which preferably combine to form a series of sharp cutting edges 6.

An annular groove 7 at the junction plane of the two cones is formed in which a pair of cone- 55 supporting wires 8 and 9 are placed. The ends

of these wires are twisted together as shown at 10 and 11 in Fig. 2, to hold the wires in the groove 7.

This device is assembled in the intake manifold pipe of an engine opposite the joint between the pipe 12 coming from a carburetor (not shown) and pipe 13 leading to the engine (not shown). The pipe ends to be joined have ears 14 with threaded holes receiving bolts 15 to draw the ends together and a gasket 16 of a suitable material somewhat yielding under pressure, is introduced between the ends in the usual way to make a tight joint.

The manifold pipe 12 has a butterfly valve 17 of usual construction to control the vapor flow through the manifold.

The major diameter of my double cone device is about three-fourths that of the inside diameter of the manifold pipe, and my device is assembled directly under the discharge side of the valve 17, 20 against the wall of the manifold pipe on that side, as shown in the drawing, where it is supported and held by the wires 8 and 9. The ends 10 and 11 of the wires 8 and 9 are clamped by bolts 15 between the ends of the manifold members 12 25 and 13, with the wire-ends embedded in the gasket 16. This gasket may be in two thicknesses as shown in Fig. 1, with the wires held between them, or a gasket of a single thickness will suffice, in which case the wires will become embedded 30 in it by the tightening of the bolts. In any event, the device is held securely in the position as shown.

The operation of my device is as follows: When the valve 17 is opened, more or less according to 35 speed requirements, hydrocarbon vapors and air from the carburetor pass down by the suction of the engine, in the direction of the arrow in Fig. 1, into contact with the sharp edges 6 which cut up unvaporized globules and dash the fragments 40 against the sides of the channels 5. The rapidly moving vapors create vacuums and partial vacuums in the channels 5 which draw vapors in and hurl them against the channel walls; also creating a swirl and eddy that intimately mixes 45 the air and hydrocarbon atoms.

The double cone causes a Venturi action which aids materially in overcoming the drag caused by the obstructing presence of the device in the manifold pipe, and continues the mixing action 50 on the explosive mixture.

While I have herein shown and described my invention in the one best form as now known to me, it is obvious that structural variations may be employed without departing from the spirit 55

of the invention, and I, therefore, do not desire to be limited to that precise form beyond the limitations as may be imposed by the following claims.

5. I claim:

1. A gas mixing device for mounting in the intake manifold of an internal combustion engine comprising a plurality of axially spaced apart annular fins each having their edges in planes normal to a common axis and having decreasing diameters from the center of the group to opposite end fins, the peripheries of the fins defining a double cone with apices directed away from said center.
10. 2. A gas mixing device for mounting in an internal combustion engine intake manifold comprising a unitary member formed to have a plurality of axially spaced apart encircling ribs concentric of the member axis, the edges of which 15 ribs define parallel planes normal to said axis, said ribs increasing in diameter one after another from one end of the member to the center thereof and then decreasing to the opposite end giving said member a double cone peripheral shape, and 20 each of said ribs having a decided recess extending back under it toward said axis.
15. 3. A gas mixing device for mounting in an internal combustion engine intake manifold comprising a unitary member formed to have a plurality of axially spaced apart encircling ribs concentric of the member axis, the edges of which 25 ribs define parallel planes normal to said axis, said ribs increasing in diameter one after another

from one end of the member to the center thereof and then decreasing to the opposite end giving said member a double cone peripheral shape, and each of said ribs having a decided recess extending back under it toward said axis, the 5 outer edges of said ribs being knife-like in character.

4. A gas mixing device for mounting in a gas engine intake manifold comprising a double cone body terminating in oppositely directed apices 10 and having a plurality of annular grooves there-around defining projecting fins therebetween of increasing diameters from said apices to the center of the body, each of said grooves being shaped to define a reentering space into the body 15 from and under an upper fin and to define a laterally projecting sharp edge on the fin.

5. In combination with a constant diameter section of a gas engine intake manifold receiving the discharge of a carburetor having a butterfly 20 valve, a mixing device circular in cross-section and mounted in said manifold eccentrically thereof and toward that side toward which said valve initially directs the carburetor discharge, said mixing device comprising a plurality of annular fins with reentering spaces therebetween projecting from a carrying member in longitudinally spaced apart relation and increasing in diameter from one end to a central zone of said member and then decreasing to the other end, a 25 central larger diameter fin being substantially in tangential contact with said manifold side.
